US00D733717S

(12) **United States Design Patent**
Fujioka

(10) **Patent No.:** **US D733,717 S**
(45) **Date of Patent:** **** Jul. 7, 2015**

(54) **CORNER BUTTON**

(71) Applicant: **Robb Fujioka**, Manhattan Beach, CA
(US)

(72) Inventor: **Robb Fujioka**, Manhattan Beach, CA
(US)

(73) Assignee: **Fuhu, Inc.**, El Segundo, CA (US)

(**) Term: **14 Years**

(21) Appl. No.: **29/454,425**

(22) Filed: **May 9, 2013**

(51) LOC (10) Cl. **14-02**

(52) U.S. Cl.

USPC **D14/456**

(58) **Field of Classification Search**

USPC ..... D14/454, 455, 456, 320, 331, 333, 334, D14/335, 338, 339, 340, 341, 342, 345, 346, D14/347, 387, 390, 391, 392, 393, 394, 395, D14/396, 397, 398, 150, 247, 248, 900, 901, D14/902, 402, 406, 426, 432, 439, 453, 457, D14/137, 138, 218, 315, 327; D13/168; D18/12.2, 7, 52, 24, 25, 29, 1, 2; 235/145 R; 341/22, 27, 28; 345/168, 345/169, 170, 171, 172, 947, 948, 163; 379/368, 915, 433.07, 433.06; 400/109, 110, 111, 472, 484, 485, 486, 400/487, 490, 491, 492, 494; 455/550.1, 455/556.2, 186.2, 575.1; 248/176.1

(57) **CLAIM**

The ornamental design for an corner button, as shown and described.

DESCRIPTION

FIG. 1 is a top, front, right side, perspective view in an exemplary embodiment of the present invention;

FIG. 2 is a bottom, front, right side, perspective view in an exemplary embodiment of the present invention;

FIG. 3 is a front elevation view of the present invention;

FIG. 4 is a left side elevation view (right side being a mirror image) in an exemplary embodiment of the present invention;

FIG. 5 is a rear elevation view in an exemplary embodiment of the present invention;

FIG. 6 is a top plan view in an exemplary embodiment of the present invention; and,

FIG. 7 is a bottom plan view in an exemplary embodiment of the present invention.
